UNITED STATES PATENT OFFICE.

WILLIAM McDONALD, OF CURWENSVILLE, PENNSYLVANIA.

CARPET-FASTENER.

1,032,922.

Specification of Letters Patent. Patented July 16, 1912.

Application filed May 17, 1911. Serial No. 627,755.

To all whom it may concern:

Be it known that I, WILLIAM McDONALD, a citizen of the United States, residing at Curwensville, in the county of Clearfield and State of Pennsylvania, have invented new and useful Improvements in Carpet-Fasteners, of which the following is a specification.

An object of the invention is to provide a carpet fastener, particularly adaptable for stair carpets and the like to removably position the carpet on the stair without the use of tacks or similar holding members passed through the carpet.

For the purpose mentioned, use is made of a rod adapted for engagement with the carpet to extend transversely thereto, sockets for removable engagement with the ends of the rod, the said sockets being positioned adjacent the ends of the carpet and means for adjustably connecting the sockets to the stair to retain the rod in engagement with the carpet.

Reference is to be had to the accompanying drawings constituting a part of this specification, in which similar characters of reference denote corresponding parts in all the views, and in which—

Figure 1 is a fragmentary perspective view of the stair provided with a carpet and showing my device attached thereto, one of the sockets being shown removed from the rod. Fig. 2 is a longitudinal sectional view taken substantially on the line 2—2 in Fig. 1.

Referring more particularly to the views, I provide a rod 10 adapted for engagement with a carpet 11 positioned on a stair 12, the said rod being adapted to engage the carpet at the inner end of one of the steps 13 of the stair and extending transversely to the carpet as shown in Fig. 1, the said rod being preferably of an angular shape and having a rounded edge 14. Sockets 15 provided with heads 16 having apertures 17 therein are adapted for slidable engagement with the ends of the rods 10 and the said sockets are provided with apertures 18 having their inner ends elongated and their outer ends flared to receive therethrough screw eyes 19.

In the use of my device the rod is first positioned on the carpet 13 as shown in Fig. 1, one of the sockets 15 is then slidably engaged with the rod so that an end of the rod will extend in the aperture 17 of the said socket and the mentioned socket is then secured to the stair 12 by screwing the

screw eye 19 into the stair, the said screw eye being extended through the elongated aperture 18 and having a head 20 thereof positioned in the flared end of the aperture 18. 60 Now when the head of the screw eye is positioned longitudinally to the socket, the said socket can be slid into and out of engagement with the rod 10 and to rigidly hold the socket to the stair 12 the head of 65 the screw eye is turned so that the said head will extend transversely to the longitudinal axis of the socket and in the flared end of the aperture 18, thus preventing any sliding movement of the socket relatively to the 70 stair. The other socket 15 is then slidably engaged with the other end of the rod 10 and is also secured to the stair 12 by means of the other screw eye 19, the said socket being slideable relatively to the stair until 75 the head of the screw eye is positioned to extend transversely to the longitudinal axis of the socket and when this is accomplished, the socket will be rigidly held relatively to the stair, thus rigidly positioning the rod 10 80 in engagement with the carpet 11 to retain the carpet in its proper position on the stair.

To remove the carpet from the stair one of the screw eyes in one of the sockets 15 is operated so that the head of the screw eye will be positioned in alignment with the longitudinal axis of the socket and the socket can then be slid outwardly and disengaged from an end of the rod 10. Now by slightly pulling the free end of the rod 10 to one side, the said rod can be disengaged from the other socket 15 and the carpet 11 can then be easily removed from the stair. It will be seen that the rod 10 is removed from the sockets 15 without removing the sockets 90 from the stair 12 and it will be further seen that with the provision of the sockets and rod as described, the carpet need not be secured to the stair by means of tacks or nails which tend to ruin the carpet and are hard 100 to remove from the carpet.

Although I have shown a plurality of similar sockets connected to the ends of the rod 10 it will be understood that only one of these sockets need be provided for slideable engagement with the rod 10 and the other socket can be firmly and securely connected to the stair. It will be further understood that although for the purpose of describing my device I have shown a particular construction thereof, the scope of the invention is defined in the appended claim. 105 110

Having thus fully described the invention, what I claim as new, is:—

In a carpet fastener, the combination with a bar adapted to hold a carpet in a stair corner, of sockets for removable engagement with the ends of said rod and slidably relative thereto, said sockets having a reduced portion provided with an elongated longitudinally extending slot having flared up-
per edges, and screw eyes extending through said slots and having heads adapted to fit in the said flared upper edges thereof to

hold said sockets snugly against the ends of said bar, said screws being adapted to be turned so as the heads thereof will aline 15 with the said slots to permit for adjustment of said sockets, substantially as and for the purpose specified.

In testimony whereof I affix my signature in presence of two witnesses.

WILLIAM McDONALD.
